UNITED STATES PATENT OFFICE.

CHARLES F. PECKHAM, OF PROVIDENCE, RHODE ISLAND.

THERMAL FUSE.

1,259,662.

Specification of Letters Patent. Patented Mar. 19, 1918.

Application filed May 17, 1917. Serial No. 169,238.

To all whom it may concern:

Be it known that I, CHARLES F. PECKHAM, a citizen of the United States, residing at Providence, in the county of Providence and State of Rhode Island, have invented 5 certain new and useful Improvements in Thermal Fuses; and I do hereby declare the following to be a full, clear, and exact description of the invention, such as will 10 enable others skilled in the art to which it appertains to make and use the same.

The invention relates to a thermal or heat-actuated fuse which is particularly designed and adapted for use in automatic 15 sprinkler heads, but which is capable of use in other devices and mechanisms where analogous conditions obtain.

The primary object of the invention is to provide a novel and improved fuse which is 20 well adapted for use in the well-known forms of sprinkler heads now in general use, and which, when so used, will eliminate the objections incident to uniting the parts of a collapsible valve-holding strut by fusible 25 solder.

Other objects of the invention are to provide a fuse of a form to expose the maximum surface for the absorption of heat, to prevent the transmission of heat or electric 30 currents between the fuse and the parts of the device to which it is applied, and to protect the fuse from the action of corrosive chemicals or fumes.

To these ends the invention consists in 35 the features of construction and combinations of parts hereinafter described and referred to in the claims.

The various features of the invention will 40 be readily understood from an inspection of the accompanying drawings and the following detailed description of the construction referred to therein.

In the drawings, Figure 1 is a side elevation, partly in section, of one form of automatic 45 sprinkler head equipped with a thermal fuse embodying a preferred form of the invention; Fig. 2 is a vertical sectional view of another form of automatic sprinkler head equipped with the fuse; and Fig. 3 is 50 an enlarged sectional view through the axis of the fuse.

The fuse is formed of a metal, such as 55 solder, which has a comparatively low fusing point, and which is commonly referred to in the sprinkler art as a "fusible" metal. As shown in Fig. 3 of the drawings, the

fuse comprises a hollow cylinder 1 having a head 2 at its outer end adapted to support the end 3 of a rod 4 which engages the head of the cylinder. As here shown, the rod 60 is in the nature of a tie-rod passing through the cylinder and having a headed end which abuts against the head of the cylinder. The cylinder is preferably in the form of a thin shell, and the head is preferably frusto-conical in shape, since this structure presents a comparatively large heat-absorbing surface, and will quickly fuse and release the rod when subjected to heat, and at the same time has the requisite strength to effectively support a comparatively heavy 70 pressure. As shown, the head of the fuse is recessed to receive the head of the tie-rod, and it is preferred to separate the rod and fuse by a gasket 5 of insulating material 75 which is a non-conductor of heat as well as electricity. The inner end of the fuse is supported upon a supporting member 6, from which it is preferably insulated by an interposed gasket 7 of insulating material. 80 The gaskets serve to protect the fuse from electric currents and electrolytic action which might otherwise destroy or impair its efficiency. They also prevent the transmission of heat between the fuse and the parts 85 with which it is connected, so that the fuse is unaffected by the temperature of these parts, which might otherwise tend to retard the melting of the fuse. The fuse may be protected from the action of corrosive elements by covering it with a casing of non-corrosive heat-conducting material indicated at 8. This casing may be in the form of a foil or plating, or may be a thin shell 90 inclosing the fuse.

In the construction shown, the inner end 95 of the tie-rod 4 carries a nut 9 which engages a member 10 and holds it against movement with relation to the supporting member 6 so long as the fuse remains intact. 100 When the fuse is subjected to a temperature high enough to fuse it, the rod 4 is no longer supported against endwise movement, and the member 9 is free to move with relation to the member 6.

In applying the fuse to a sprinkler head having the form of collapsible strut indicated in Fig. 1, the inner end of the fuse 105 may be connected with or supported on the member 11 of the strut, while the tie-rod 110 binds the member 12 to the member 11 so that these members form a rigid strut be-

tween the members 13 and 14 so long as the fuse remains intact. When the sprinkler head is subjected to heat, however, the fuse quickly melts and collapses, so that the members 11 and 12 are free to move with relation to each other, thus allowing the entire valve-holding strut to collapse and fly apart.

In applying the fuse to a sprinkler head 10 having the construction shown in Fig. 2, the fuse may be secured to or supported by the locking plate 15 while the tie-bolt binds this plate to the post 16 so long as the fuse remains intact. When the fuse melts, the 15 locking plate 15 is released, so that the post and plate may move relatively to each other, thus allowing the valve-holding strut to collapse and fly apart.

While it is preferred to employ the specific construction of fuse shown and described, it will be understood that this construction may be varied or modified without departing from the broader scope of the invention. It will also be understood that in 20 applying the fuse to a sprinkler head the arrangement of the fuse, and the manner in which the rod is connected to the collapsible strut to prevent its collapse until the fuse melts may be varied or modified as found 25 desirable or best suited to the construction and arrangement of the parts with which the fuse and rod are combined.

Having explained the nature and object 30 of the invention, and specifically described one structure in which it may be embodied, what is claimed is:—

1. A thermal fuse comprising a fusible hollow cylinder one end of which is provided with a pressure supporting head for 40 supporting a rod engaging the head, and said rod.

2. A thermal fuse comprising a comparatively thin fusible shell the outer end of which is provided with a head recessed to 45 support the head of a tie-rod passing through the shell, and said rod.

3. A thermal fuse comprising a comparatively thin fusible shell the outer end of which is provided with a frusto-conical 50 head recessed to support the head of a tie-rod passing through the shell.

4. A thermal fuse comprising a fusible

hollow cylinder one end of which is provided with a pressure supporting head for supporting the end of a rod engaging said 55 head, and said rod.

5. A thermal fuse comprising a fusible cylinder, a supporting member for one end of the cylinder, a rod passing through the supporting member and provided at one end 60 with a head supported by the cylinder, and a member held by the other end of the rod from movement relatively to the supporting member.

6. A thermal fuse comprising a fusible 65 cylinder, a supporting member for one end of the cylinder, an insulating gasket between the end of the cylinder and the support, a rod passing through the supporting member and provided at one end with a 70 head supported by the cylinder, and a member held by the other end of the tie-rod from movement relatively to the supporting member.

7. A thermal fuse comprising a fusible 75 cylinder, a supporting member for one end of the cylinder, an insulating gasket between the end of the cylinder and the support, a rod passing through the supporting member and provided at one end with a 80 head supported by the cylinder, an insulating gasket between the head of the rod and the cylinder, and a member held by the other end of the tie-rod from movement relatively to the supporting member.

8. A thermal fuse for preventing the collapse of the valve-holding strut of a sprinkler head comprising a fusible cylinder, and a rod connected to resist the collapse of the strut and having one end supported by the 90 cylinder.

9. A thermal fuse for preventing the collapse of the valve-holding strut of a sprinkler head comprising a fusible cylinder, one 95 end of which is supported on one member of the strut, and a tie-rod connected to another member of the strut and having a head supported by the cylinder.

10. A thermal fuse comprising a comparatively thin fusible shell one end of which is provided with a head for supporting the end of a rod engaged therewith, and said rod.

CHARLES F. PECKHAM.

Copies of this patent may be obtained for five cents each, by addressing the "Commissioner of Patents, Washington, D. C."

It is hereby certified that in Letters Patent No. 1,259,662, granted March 19, 1918, upon the application of Charles F. Peckham, of Providence, Rhode Island, for an improvement in "Thermal Fuses," an error appears in the printed specification requiring correction as follows: Page 2, lines 72 and 84, claims 6 and 7, strike out the word and hyphen "tie-;" and that the said Letters Patent should be read with this correction therein that the same may conform to the record of the case in the Patent Office.

Signed and sealed this 23d day of April, A. D., 1918.

[SEAL.]

F. W. H. CLAY,

Acting Commissioner of Patents.
